UNITED STATES PATENT OFFICE.

ELMER A. WATTS, OF SPRINGFIELD, AND IRWIN L. DUNN, OF MARIETTA, OHIO.

DISPLACEMENT-PUMP.

1,206,065.

Specification of Letters Patent. Patented Nov. 28, 1916.

Application filed April 19, 1915. Serial No. 22,296.

To all whom it may concern:

Be it known that we, ELMER A. WATTS and IRWIN L. DUNN, citizens of the United States, residing at Springfield, Clark county, and Marietta, Washington county, Ohio, respectively, have invented certain new and useful Improvements in Displacement-Pumps, of which the following is a specification, reference being had therein to the accompanying drawing.

This invention relates to displacement pumps and is in the nature of a further development of the invention embodied in the application for patent filed by us March 8th, 1915, Ser. No. 12,795 on which Letters Patent #1,187,579 were granted June 20, 1916.

The displacement pump shown and described in that application operates in a manner which is entirely satisfactory in wells of ordinary depth but in very deep wells the air pressure necessary to lift the oil, or other fluid, to the top of the well is so great as to be to a degree objectionable.

The object of the present invention is to provide a displacement pump which will elevate a quantity of fluid to a great height with a relatively low air pressure.

To this end it is a further object of the invention to provide a pump of this character in which the oil or other fluid will be lifted step-by-step, or relayed, to the top of the well.

It is also an object of the invention to provide means for so controlling the admission of air to the pump and its exhaust therefrom as to enable the expansion of the air to be utilized for lifting the fluid through the latter part of its movement, thereby materially reducing the amount of air required to elevate a given quantity of oil or fluid.

In the accompanying drawings, Figure 1 is a side elevation of a displacement pump embodying our invention showing the same in position in the well; Fig. 2 is a vertical, sectional view of the upper portion of such a pump; Fig. 3 is a similar view of the lower portion of the pump and constitutes a continuation of Fig. 2; Fig. 4 is a side elevation, partly in section, of the controlling device; Fig. 5 is a sectional, detail view of the upper end of one of the fluid receptacles showing the means for permitting the escape of surplus fluid; Fig. 6 is a sectional, detail view of the combined inlet and exhaust valve; and Figs. 7 and 8 illustrate in

side elevation, partly in section, a modified form of the invention.

In these drawings we have illustrated two embodiments of our invention and have shown the same as embodied in structures similar in the main features to that shown, described and claimed in the above-mentioned application for patent. It will be understood, however, that the invention may be embodied in structures of various kinds and may be utilized for purposes other than the pumping of oil.

As here illustrated the pump embodying the invention is mounted in an oil well having the usual well casing 1 and provided at the lower end of the casing with a pocket 2 in which the oil accumulates and from which it is pumped to the surface of the ground. Mounted in the pocket 2 and communicating with the oil therein is an oil receptacle or cylinder 3 having at its lower end an oil inlet port 4 which is provided with a check valve 5 to prevent the escape of oil therefrom through the port 4. Extending into the receptacle or cylinder 3 is a discharge pipe 6, the lower end of which preferably extends to a point near the bottom of the oil receptacle and the upper portion of which extends beyond the upper end of the receptacle 3. To discharge the oil from the receptacle through the discharge pipe 6 air is admitted to the upper end of the receptacle through an air conduit or pipe 7 which extends upward through the well casing 1 and is provided at its upper end with a controlling device 8 which may be of any suitable character but is here illustrated as of the same type shown and described in the above-mentioned application. This device need not be here described in detail. Suffice it to say that it comprises a casing 9 having an air inlet port 10 communicating with an air supply pipe 11 and has also an exhaust port 12 arranged at a point remote from said inlet port. The inlet and exhaust ports 10 and 12 both communicate with a passage 13 which is connected by a pipe 14 with the upper end of the air pipe 7. Valves 15 and 16 control the inlet and exhaust ports, respectively, and these valves are controlled by means of a lever 17 which has oppositely extending arms 18 and 19, the latter being provided with a counterweight 20 and the former being connected with a wire 21 which extends through the air pipe 7 and is connected with

100
105
110

2
a weight 22 which is mounted within the oil receptacle 3. As the fluid rises around the weight 22 the latter is buoyed up until the counterbalance 20 is sufficient to rock the lever 17 in a direction to open the inlet port and admit air through the pipes 14 and 7 to the cylinder, thereby forcing the oil through the discharge pipe 6. As the fluid lowers around the weight the buoyancy thereof is decreased until it is sufficient to again rock the lever against the opposing force of the counterbalance 20 to move the lever in a direction to cause the closing of the inlet port 10 and the opening 15 of the exhaust port 12. This latter part of the action, however, is modified in the present device, as will be hereinafter described.

As has been explained the air pressure necessary to elevate the oil from the receptacle 3 to the surface of the ground in the case of wells of great depth is excessive. In order to avoid the necessity for such a high air pressure and to enable the oil to be lifted from deep wells with a relatively low air pressure, we have provided a relay system of oil receptacles, each of which is adapted to receive the oil from the next lower receptacle, thereby making it necessary to lift the oil for comparatively short distances only at each step of the operation of the pump. As here shown, a second receptacle or cylinder 23 is arranged above the receptacle 3 and spaced therefrom a distance determined by the air pressure which it is desired to use. The upper end of the discharge pipe 6 communicates with this second or next higher receptacle 23. In the present instance it extends through the lower head of the cylinder 23 and terminates just short of the upper cylinder head. This receptacle or cylinder 23 is also provided with a discharge pipe, 24, which communicates therewith near the lower end thereof and extends upward and into a third receptacle or cylinder 25 which is supported above the receptacle 23 and spaced therefrom a suitable distance. The cylinder 25 has a discharge pipe 26 leading therefrom and communicating either with a fourth receptacle or cylinder, or, as in the case of the device here illustrated, with a discharge line 27 at the top of the well. It will be understood that while we have shown three receptacles or cylinders in the present embodiment of the invention this number will be determined by the distance which it is necessary to elevate the fluid and by the air pressure available. In this embodiment of the invention the upper receptacle, 25, is supported from the end of the discharge line 27, which is carried by a casing head 28, by means of rods 29 and the next lower receptacle 23 is supported from the receptacle 25 by similar rods 29 and likewise the lowermost receptacle 3 is

supported from the receptacle 23 by means of rods 29 so that the whole mechanism is supported by the casing head 28. Inasmuch as the cylinders or oil receptacles are of such a size as to practically fill the well casing 1 the air supply pipe 7 passes through each of the several cylinders. This, however, is merely a matter of convenience and is done to enable the receptacles to be made as large as practical. It will be apparent, therefore, that when the air is admitted through the pipe 7 into the upper end of the lowermost receptacle 3 the oil will be forced out of that receptacle through the discharge pipe 6 and into the next higher receptacle 23. Inasmuch as the receptacles are of substantially the same capacity the lowermost receptacle will be completely emptied into said next higher receptacle and the air will then follow from this lowermost receptacle into said next higher receptacle and the fluid will be discharged therefrom through the discharge pipe 24 into the next higher receptacle 25 and, in due course, from the receptacle 25 through the discharge pipe 26 to the discharge line 27 at the top of the well. In each instance the air pressure required has only been that necessary to lift the oil through the distance separating the discharging and receiving receptacles.

Means have also been provided to prevent the controlling device 8 from operating to exhaust the air from the pump as soon as the lowermost receptacle 3 has been emptied. To this end we have provided means for locking the lever 17, which controls the operation of the device 8 in a position to maintain the exhaust port of the valve closed. In that form of the invention shown in Figs. 1 to 4 the lever is maintained in a position to hold the inlet valve open, as well as to hold the exhaust valve closed. This is accomplished by means of a trip arm or trigger 30 which is arranged to engage the arm 18 of the lever 17 and hold the same in its uppermost position, thereby preventing the lever being moved by the float as the fluid level in the lowermost receptacle is lowered. The trip arm 30 is automatically disengaged from the arm 18 to permit the valve 8 to operate at the desired time during the operation of the pump. To this end we have interposed in the discharge line 27 a receptacle 31 in the side wall of which the arm 30 is pivoted and which is provided with an outlet pipe 32 of smaller capacity than the inlet pipe. The inlet pipe communicates directly with the chamber formed within the receptacle 31 but its escape therefrom to the outlet pipe 32 is controlled by a valve 33 which is here shown in the nature of a piston valve mounted for movement into and out of a port 34. This valve is connected at its upper end with a crank 130

shaft 35, which crank shaft is also connected by means of a link 36 with the trip arm 30. Pivotally connected with the crank shaft 35 is a rod 37 carrying at its outer end a float 38 arranged to rise and fall with the oil in the chamber. The connections between the crank shaft and the several parts are so regulated as to properly time the operation of the trip arm 30. With the parts in the position shown in Fig. 4 the port 34 is closed and the inlet port of the device 8 is open so that the air is entering the pump. As the fluid in the uppermost receptacle is discharged into the chamber 31 of the receptacle 31 the float will begin to rise. The first portion of its movement will open the outlet port 34, thus permitting the escape of the oil through the pipe 32 to the receiving tank. Inasmuch, however, as the inlet is of greater capacity than the outlet the receptacle will continue to fill and the float 38 will continue to rise and will eventually move the trip arm 30 out of engagement with the arm 18, thus permitting the lever 17 to be actuated by the weight 22, the inlet port of the device 8 to be closed and the exhaust port to be opened. The movement of the parts is so timed that this operation does not take place until the oil has been either completely or to a large measure discharged from the pump. As the oil escapes from the receptacle 31 after the trip arm has been operated, the float will move toward its lowermost position and will thus cause the trip arm to bear against the end of the arm 18 of the lever 17 and when that arm is again elevated to admit the air to the pump, the trip arm will engage beneath the same and hold it in its elevated position.

In Figs. 7 and 8 we have shown a slightly modified form of the invention in which direct air pressure is utilized to discharge the air from the lowermost receptacle only and the subsequent elevation of the oil is accomplished by the expansion of the air. The character of the receptacles and the manner of mounting the same correspond to that already described with the exception that the receptacles are spaced apart different distances, this being due to the decrease of air pressure as the oil is elevated step by step. In this form of the invention, as in the one already described, we have illustrated the pump as comprising three receptacles. By way of illustration we have indicated that the lowermost receptacle 40 and the next higher receptacle 41 are spaced apart two hundred feet, although in practice the two receptacles would probably be spaced apart a much greater distance. The third receptacle 42 is shown as spaced above the second receptacle 41 one hundred feet, or one-half the distance that separates the first two receptacles, while the third receptacle 42 is spaced below the top of the well

sixty-six and two-thirds feet, or a distance two-thirds of that which separates the second and third receptacles.

In the operation of this pump the air is admitted to the lowermost cylinder 40 in a quantity sufficient to completely empty that cylinder and the float is permitted to operate to cause the closing of the air inlet valve but, by means hereinafter described, the exhaust valve is maintained closed, thus confining the air within the pump. The air which is now within the lowermost cylinder and in the discharge pipe of that cylinder will expand and will force the oil from the second cylinder 41 to the third cylinder and subsequently a further expansion of this air will force the oil from the third cylinder to the discharge line. Assuming that the pump is operating with a one hundred pound pressure this full hundred pounds will be used for the elevation of the oil through the two hundred feet separating the first and second receptacles. The air pressure will then have been reduced to substantially fifty pounds, but this is sufficient to elevate the oil through the reduced distance, one hundred feet, separating the second and third receptacles. There is then a further reduction of air pressure to substantially thirty-three and one-third pounds, but again this is sufficient to elevate the oil through the further reduced distance, sixty-six and two-thirds feet, separating the third receptacle from the top of the well. To prevent the opening of the exhaust port of the valve 8 when the inlet port of that device is closed by the action of the lever 17 we have provided a trip arm 44, which is similar to the arm 30 of the device above described, with a shoulder 45 arranged to engage the end of the arm 18 when the lever 17 has been moved into an intermediate position, which position will cause the closing of the inlet valve without causing the opening of the exhaust valve. As here shown, the arm extends some distance above the projection 45 and extends slightly into the curved path which must be followed by the end of the arm 18 and causes the float in the controlling receptacle 31 to act as a counterweight which resists the downward movement of the arm 18 and prevents the same from striking the projection with too great force. The operation of the controlling device is so timed as to move the trip arm 44 out of the path of the arm 18 when the uppermost receptacle has been completely discharged.

In pumps of this character where the available air pressure is sufficient to lift a given body of oil through a predetermined distance it is obvious that any material excess of oil would interfere with the operation of the device and probably render the same inoperative. This excess or surplus of oil

might be had in different ways. The most probable way, however, would be the interruption of the air pressure with one of the upper receptacles full of oil. In that form 5 of the device shown in Figs. 1 to 4, for example, if the air pressure should be suddenly cut off with a large supply of oil in the second receptacle, 23, or if in that form shown in Figs. 7 and 8 the exhaust valve 10 should be opened and permit the exhaust of the air after the second receptacle, 41, had filled, this intermediate receptacle would remain filled until the operation was resumed. As such an interruption of pressure would 15 probably be due to an accident or to a shut down of the machinery for some cause the lowermost receptacle in either instance would in all probability be filled, or partly filled, before the air pressure was again applied to the oil in the pump. As a result it would be necessary to lift not only the oil in the lowermost receptacle but also the oil in the second receptacle and as the available air pressure would ordinarily be 20 sufficient to lift this double load we have provided means for permitting the escape of the oil from the upper receptacle, this means being of such a character that it will not interfere with the ordinary operation of the 25 pump. In the present instance, we have provided the upper cylinder head of each of the upper receptacles with a relief port 46 which is formed by a pipe 47 extending through the cylinder head, supported there- 30 by and extending into the receptacle some distance below the top thereof.

Secured to the lower end of the pipe 47 is a block 48 having two or more ports 49 communicating with the end of the pipe 47 35 and extending upwardly through the top of the block 48. These ports 49 permit the oil in the receptacle to escape through the port 46 and flow back into the well when a surplus of oil enters the receptacle. It is necessary, however, to prevent the escape either 40 of the oil or air through the port 46 during the normal operation of the device and also to provide for the escape of the air which may be contained in the upper part of the 45 receptacle or in the discharge pipe leading from the lower receptacle into the same. When the lower receptacle is being discharged into the upper receptacle before the latter has been emptied, under these circumstances, there is usually more or less air in the top of the receptacle and the discharge pipe contains air. We have, therefore, provided in the upper end of the receptacle an air port 50 leading into the discharge pipe 24 of that receptacle. This port 55 communicates with the interior of the receptacle through a shallow recess 51 and is adapted to be closed by means of a disk-like valve 52 which is of a diameter considerably greater than the diameter of the re- 60 cess 51. Mounted on the pipe 47 is a float 53, which is preferably open at one end to prevent it from collapsing and this float is connected with the valve member 52 by means of a spring 54. Under normal conditions the positions of the parts will be that shown in Fig. 5 and the lower end of the sleeve 53*, which is secured to the float, will close the ports 49. When, however, oil enters the receptacle it will first force out the air contained in the upper part of the receptacle through the air relief port 50 and will then lift the float 53, which serves to open the ports 49 to permit the flow of oil through these ports and the port 46 and to close the valve 52 to prevent the further escape of air. The oil will continue to escape slowly through the port 46 until the load has been reduced to such an extent that the air pressure will force it through the discharge pipe. When air again enters the receptacle through the inlet pipe from the next lower receptacle the oil level will be lowered and the float will move downward and close the ports 49, thereby preventing the escape of air through these ports, but the valve 52 will remain closed because that portion thereof which is exposed to the air pressure in the receptacle is much larger in area than the portion which is exposed to the pressure of the relief port 50. When during the normal operation of the pump the level of the oil in the receptacle rises far enough to lift the float 53 and open the ports 49 this results in the escape of a small quantity of oil only during the first portion of the discharging operation. As soon as the oil level had dropped slightly the ports 49 would again be closed and the amount of oil lost in this way would make no appreciable difference in the capacity of the pump. It will be understood, of course, that during the normal operation of the pump the air pressure holds the valve 52 closed so that the air pressure is not relieved through the port 50. When the exhaust valve to the lower chamber opens the pressure against the valve 52 is relieved allowing the same to drop so that the upper chambers can again fill, the remaining air escaping into the discharge pipes. It will be noted that the relief port 50 leads into the discharge pipe for the receptacle. This is desirable in oil wells because the gas in the well is utilized for power purposes and it is not desirable that air should be mixed therewith. The exhaust air thus escaping into the discharge pipe may escape into the atmosphere through the casting 51 which is not air tight.

The operation of the pump will be readily understood from the foregoing description and it will be apparent that we have provided a displacement pump by means of which oil or other fluids may be lifted step by step to a great height, this being accom- 125 130

plished with a relatively low air pressure; further, that the pump is of a very simple character, is wholly automatic in its operation and is provided with means to prevent it becoming inoperative because of an over-load.

6 While we have shown and described two embodiments of our invention it will be understood that this has been chosen for the purposes of illustration only and that we do not desire to be limited to the details of construction shown and described, for obvious modifications will occur to a person skilled in the art.

10 Having thus fully described our invention, what we claim as new and desire to secure by Letters Patent, is:—

15 1. A mechanism for elevating fluids comprising a plurality of closed receptacles arranged one above the other and spaced apart, the lowermost receptacle communicating with a source of fluid supply, a conduit leading from the lower portion of each lower receptacle to the upper portion of the next higher receptacle, and means for admitting air under pressure to the upper portion of said lowermost receptacle, whereby the air will first discharge the fluid from said lowermost receptacle through one of 25 said conduits to said next higher receptacle and will then follow the fluid through said conduit into said next higher receptacle and discharge the fluid therefrom.

20 2. A mechanism for elevating fluids comprising a plurality of receptacles arranged one above the other and spaced apart, the lowermost receptacle communicating with a source of fluid supply, a pipe connecting each adjacent receptacle, whereby fluid can be elevated from a lower to a higher receptacle, means for admitting air under pressure to said lower receptacle to elevate said fluid to the next receptacle, said pipes being unobstructed to allow the compressed air 35 in the lowermost receptacle to follow the fluid through the pipe to elevate the same from the next receptacle to the one above.

25 3. In a mechanism for elevating fluids, a receptacle, a discharge line leading from said receptacle, means for admitting compressed air to said receptacle, means controlled by the rise of fluid in said receptacle for admitting compressed air thereto, and means located in said discharge line and 40 operable by the fluid when it has been discharged from said receptacle and discharge line for controlling the shutting off of the air to said receptacle.

30 4. In a system for raising fluids, a plurality of receptacles, one above the other and spaced apart, portions connecting said receptacles and so arranged that the fluid may be raised step by step through the system by the following action of compressed air through the connecting portions and the

receptacles, means for admitting compressed air to the lowermost receptacle, and means controlling said air-admitting means to shut the same off when the fluid has been discharged through the system.

70 5. In a system for raising fluids, a plurality of receptacles arranged one above the other, each lower receptacle having portions communicating with the next upper receptacle whereby fluid may be discharged step by step through the system by the following action of air through the communicating portions from the lowermost receptacle, means for admitting and exhausting air to and from the lowermost receptacle, and means for controlling the exhaust for said lowermost receptacle when the fluid has been discharged from the system.

75 6. In a system for raising fluids, a plurality of receptacles arranged one above the other, each lower receptacle having portions communicating with the next upper receptacle whereby fluid may be discharged step by step through the system by the following action of air through the communicating portions from the lowermost receptacle, means for admitting and exhausting air to and from the lowermost receptacle, means for controlling the exhaust for said lowermost receptacle when the fluid has been discharged from the system, and valve controlled exhausts for the upper receptacles.

80 7. In a mechanism for elevating fluids comprising a plurality of receptacles arranged one above the other and spaced apart, the lowermost receptacle communicating with a source of fluid supply, a pipe connecting each adjacent receptacle whereby fluid can be elevated from a lower to a higher receptacle, means for admitting air 85 under pressure to said lowermost receptacle to elevate said fluid to the next receptacle, said pipes being unobstructed to allow the compressed air in the lowermost receptacle to follow the fluid through the pipe to elevate the same from the next receptacle to the one above, means for admitting compressed air to said lowermost receptacle, and valve controlled exhausts in each receptacle.

85 8. In a mechanism for elevating fluids, a plurality of receptacles arranged one above the other and of such capacity that each upper receptacle can receive substantially the entire discharge of fluid from the lowermost receptacle, a conduit leading from the lower portion of each lower receptacle to the upper portion of the next higher receptacle, means for admitting air under pressure to the lowermost receptacle whereby the air will first discharge the fluid from the lower 100 receptacle through one of said conduits to said next higher receptacle and will then follow the fluid through said conduit into the next higher receptacle and discharge the same therefrom.

9. A mechanism for elevating fluids comprising a plurality of closed receptacles arranged one above the other and spaced apart, the lowermost receptacle communicating with a source of fluid supply and each upper receptacle communicating with the next lower receptacle, an air conduit leading to said lowermost receptacle, a device to interrupt the flow of air through said conduit, 5 a weight to control the operation of said device, and means controlled by the fluid which is being elevated to control the operation of said weight.
10. A mechanism for elevating fluids comprising a plurality of closed receptacles arranged one above the other and spaced apart, the lowermost receptacle communicating with a source of fluid supply and each upper receptacle communicating with the next 10 lower receptacle, an air conduit leading to said lowermost receptacle, a device controlled by the fall of fluid in said lowermost receptacle to interrupt the flow of air through said conduit to said lowermost receptacle, and means controlled by the discharge of the fluid from the uppermost receptacle to control the exhaust of the air.
11. A mechanism for elevating fluids comprising a plurality of closed receptacles arranged one above the other and spaced apart, the lowermost receptacle communicating with a source of fluid supply and each upper receptacle communicating with the next lower receptacle, an air conduit leading to 15 said lowermost receptacle, a device to cause the admission of air to said lowermost receptacle and the exhaust of the air therefrom, a weight mounted in said lowermost receptacle and operatively connected with said device to control the operation thereof, and means controlled by the discharge of the fluid from the uppermost receptacle to control the operation of said weight to cause the air to be exhausted from said lowermost receptacle.
12. A mechanism for elevating fluids comprising a plurality of closed receptacles arranged one above the other and spaced apart, the lowermost receptacle communicating with a source of fluid supply and each upper receptacle communicating with the next lower receptacle, an air conduit leading to 20 said lowermost receptacle, a device to cause the admission of air to said lowermost receptacle and the exhaust of the air therefrom, means controlled by the fluid in said lowermost receptacle to cause the operation of said device, a detent to prevent the operation of said device, and means controlled by the discharge of the fluid from the uppermost receptacle to actuate said detent to release said device and permit it to operate.
13. A mechanism for elevating fluids comprising a plurality of closed receptacles arranged one above the other and spaced apart, 25 the lowermost receptacle communicating with a source of fluid supply and each upper receptacle communicating with the next lower receptacle, an air conduit leading to said lowermost receptacle, inlet and exhaust valves connected with said conduit, an actuating device for said combined inlet and exhaust valves, a weight mounted in said lowermost receptacle and connected with said actuating device to control the movement thereof, a detent, and a device actuated by the fluid discharged from the uppermost receptacle to actuate said detent to release said actuating device.
14. A mechanism for elevating fluids comprising a plurality of closed receptacles arranged one above the other and spaced apart, the lowermost receptacle communicating with a source of fluid supply and each upper receptacle communicating with the next 30 lower receptacle, an air conduit communicating with said lowermost receptacle, a discharge line communicating with and adapted to receive the fluid from the uppermost receptacle, means controlled by the rise and fall of the fluid in said lowermost receptacle to connect said air conduit with a source of supply for air under pressure or with an exhaust port, a fluid receptacle interposed in said discharge line, and means controlled by the fluid in said receptacle to prevent the operation of said first-mentioned means to connect said air conduit with said exhaust port.
15. A mechanism for elevating fluids comprising a plurality of closed receptacles arranged one above the other and spaced apart, the lowermost receptacle communicating with a source of fluid supply and each upper receptacle communicating with the next lower receptacle, an air conduit communicating with said lowermost receptacle, a discharge line communicating with and adapted to receive the fluid from the uppermost receptacle, means controlled by the 35 rise and fall of the fluid in said lowermost receptacle to connect said air conduit with a source of supply for air under pressure or with an exhaust port, a fluid receptacle interposed in said discharge line, and means controlled by the fluid in said receptacle to prevent the operation of said first-mentioned means to interrupt the connection between said air conduit and said source of air supply.
16. A mechanism for elevating fluids comprising a plurality of closed receptacles arranged one above the other and spaced apart, the lowermost receptacle communicating with a source of fluid supply and each upper receptacle communicating with the next lower receptacle, an air conduit communicating with said lowermost receptacle, a discharge line communicating with and adapted to receive the fluid from the uppermost 40

- receptacle, means controlled by the fluid in said lowermost receptacle to connect said air conduit with a source of supply for air under pressure or with an exhaust port, and 5 comprising a movable member, a fluid receptacle interposed in said discharge line to receive the oil passing through the same, a valve to control the escape of the fluid from said receptacle, a float connected with said 10 valve to operate the same, a detent to engage the movable member of said first-mentioned means, and a connection between said detent and said float to cause said detent to be actuated to release said movable member 15 and permit the operation of said first mentioned means.
17. A mechanism for elevating fluids comprising a plurality of closed receptacles arranged one above the other and spaced apart, the lowermost receptacle communicating with a source of fluid supply and each upper receptacle communicating with the next lower receptacle, an air conduit communicating with said lowermost receptacle, a discharge line communicating with and adapted to receive the fluid from the uppermost receptacle, means controlled by the fluid in said lowermost receptacle to connect said air conduit with a source of supply for air under pressure or with an exhaust port and 20 comprising a movable member, a fluid receptacle interposed in said discharge line to receive the fluid passing through the same, said receptacle having its outlet smaller than its inlet, a valve controlled passage within said receptacle to control the flow of fluid therefrom through said reduced outlet, a detent arranged to engage the movable member of said means, a float mounted 25 in said receptacle, and operative connections between said float and said valve and said detent, respectively.
18. A mechanism for elevating fluids comprising a plurality of closed receptacles arranged one above the other and spaced apart, the lowermost receptacle communicating with a source of fluid supply and each upper receptacle communicating with the next lower receptacle, an air conduit communicating with said lowermost receptacle, a discharge line communicating with and adapted to receive the fluid from the uppermost receptacle, inlet and exhaust valves to control the flow of air to and from said air conduit, an actuating lever to cause the operation of said valves, arms extending from the opposite sides of said lever, a counterweight connected with one of said arms, a weight mounted in said lowermost receptacle and 30 connected with the other of said arms, a detent arranged to engage said last-mentioned arm and control the movement of said lever under the influence of said weight, a fluid receptacle interposed in said discharge line and having a reduced outlet to restrict the 35 flow of fluid through the same, and a float mounted in said receptacle and operatively connected with said detent to actuate the latter and release said lever to permit said lever to complete its movement under the influence of said weight.
19. A mechanism for elevating fluids comprising a plurality of receptacles arranged one above the other and spaced apart, the lowermost receptacle communicating with a source of fluid supply and each upper receptacle communicating with the next lower receptacle, and means for admitting air under pressure to said lowermost receptacle to elevate the fluid from said lowermost receptacle to the next higher receptacle and for admitting air from said lowermost receptacle to said next higher receptacle to discharge the fluid from said next higher receptacle, and means to cause any surplus fluid which may be delivered to said next higher receptacle to be discharged at the top of said receptacle.
20. A mechanism for elevating fluids comprising a plurality of receptacles arranged one above the other and spaced apart, the lowermost receptacle communicating with a source of fluid supply and each upper receptacle communicating with the next lower receptacle, means for admitting air under pressure to said lowermost receptacle to elevate the fluid from said lowermost receptacle to the next higher receptacle and for admitting air from said lowermost receptacle to said next higher receptacle to discharge the fluid from said next higher receptacle, said next higher receptacle having a relief port to permit the escape of surplus fluid therefrom, and means to prevent the escape of air through said relief port when the surplus fluid has been discharged through the same.
21. A mechanism for elevating fluids comprising a plurality of receptacles arranged one above the other and spaced apart, the lowermost receptacle communicating with a source of fluid supply and each upper receptacle communicating with the next lower receptacle, means for admitting air under pressure to said lowermost receptacle to elevate the fluid from said lowermost receptacle to the next higher receptacle and for admitting air from said lowermost receptacle to said next higher receptacle to discharge the fluid from said next higher receptacle, said next higher receptacle having an air relief port and a fluid relief port, and a float to close said air relief port and open said fluid relief port and to close said fluid relief port without opening said air relief port after the surplus fluid has been discharged therefrom.
22. A mechanism for elevating fluids comprising a plurality of closed receptacles arranged one above the other and spaced apart,

- apart, the lowermost receptacle communicating with a source of fluid supply, a conduit leading from the lower portion of each lower receptacle to the upper portion of the next higher receptacle, means for admitting air under pressure to the upper portion of said lowermost receptacle, whereby the air will first discharge the fluid from said lowermost receptacle through said conduit to 10 said next higher receptacle and will then follow the fluid into said next higher receptacle and discharge the fluid therefrom; an air relief port leading from the upper end of said next higher receptacle to the discharge 15 pipe of that receptacle, a fluid relief port comprising a tube extending into the upper end of said receptacle and provided at its lower end with a block having ports communicating therewith, a float mounted on said 20 tube and arranged to open said ports when in its lowermost position, a disk like valve arranged above said float and adapted to close said air relief port, and a spring interposed between said float and said air valve.
23. In a mechanism for elevating fluids, a receptacle communicating with a source of fluid supply, valve-controlled means for admitting compressed air to and exhausting the same from said receptacle, a device comprising means controlled by the rise and fall of fluid in said receptacle for controlling said valve-controlled means, a discharge line leading from said receptacle, means to render said device inoperative to 30 open the exhaust, and means controlled by the fluid elevated to control the means for rendering said device inoperative.
24. In a mechanism for elevating fluids, a receptacle communicating with a source of fluid supply, an air conduit leading to said receptacle, a device to cause the admission of air to said receptacle and the exhaust of air therefrom, a discharge line from said receptacle, means controlled by the fluid in 40 said receptacle to cause the operation of said device, a detent to prevent the operation of said device, and means controlled by the discharge of fluid through said discharge line to actuate said detent to release said device 45 and permit it to operate.
25. In a mechanism for elevating fluids, a plurality of receptacles, a conduit leading from the lower portion of each lower receptacle to the upper portion of the next higher 50 receptacle whereby the fluid may be elevated step by step through said conduits by air following the same therethrough, means for admitting compressed air to the lowermost receptacle, automatic means for controlling the admission of compressed air thereto, and valve controlled exhausts mounted in each receptacle.
26. In a mechanism for elevating fluids, a plurality of receptacles, a conduit leading from the lower portion of each lower receptacle to the upper portion of the next higher receptacle whereby the fluid may be elevated step by step through said conduits by air following the same therethrough, a combined air inlet and exhaust communicating 65 with the lowermost receptacle, means controlled by the rise and fall of fluid in this receptacle for controlling the admission of compressed air and the exhaust, valve-controlled exhausts in each of the upper receptacles, and means for delaying the operation of the exhaust in said lowermost receptacle until the fluid has been elevated through the mechanism.
27. In a mechanism for elevating fluids, a plurality of receptacles, conduits connecting said receptacles, whereby the fluid may be elevated therethrough step by step by the following action of air through the receptacles and conduits, means for admitting and exhausting air to and from said lowermost receptacle, and means within the upper receptacles for allowing the exhaust of air therefrom and surplus fluid.
28. In a device of the character described, a receptacle adapted to receive a fluid to be elevated, means for admitting compressed air to said receptacle, an air relief port and a fluid relief port for said receptacle, and a float to close said air relief 90 port and open said fluid relief port and to close said fluid relief port without opening said air relief port after the surplus fluid has been discharged therefrom.
29. In a device of the character described, a receptacle adapted to receive fluid to be elevated, means for admitting compressed air to said receptacle, an air relief port leading from the upper end of said receptacle, a fluid relief port comprising a tube extending into the upper end of said receptacle and provided at its lower end with a block having a port communicating therewith, a float mounted on said tube and arranged to inclose said port when in its lowermost 100 position, a disk like valve arranged above said float and adapted to close said air relief port, and a spring interposed between said float and said air valve.

In testimony whereof, we affix our signatures in presence of two witnesses.

ELMER A. WATTS.

IRWIN L. DUNN.

Witnesses to signature of Watts:

ALBERT K. SMITH,

OLIVER H. MILLER.

Witnesses to signature of Dunn:

ORTON C. DUNN,

GERALDINE ENGLISH.
